UNITED STATES PATENT OFFICE.

ROBERT ROCHMILL, OF SELMA, ALABAMA.

TROUSERS.

SPECIFICATION forming part of Letters Patent No. 779,738, dated January 10, 1905.

Application filed September 10, 1904. Serial No. 224,130.

To all whom it may concern:

Be it known that I, ROBERT ROCHMILL, a citizen of the United States, residing at Selma, in the county of Dallas and State of Alabama, have invented new and useful Improvements 5 in Trouzers, of which the following is a specification.

This invention relates to new and useful improvements in trousers.

10 The object of the present invention is to improve the construction of a pair of trousers, and relates more particularly to the formation of cuffs upon the bottom of the legs and also upon the waist.

15 A further object of the invention is to construct a pair of trousers with a cuff or belt retaining and covering means formed upon the upper edge thereof.

20 A still further object of the invention is to secure upon a pair of trousers of the desired length means for retaining and entirely covering a belt except the buckle thereof, said buckle being positioned flush with the covering and retaining means upon the trousers.

25 With these and other objects in view the invention consists in certain novel constructions, combinations, and arrangements of parts, as will be hereinafter fully described, illustrated in the accompanying drawings, and more particularly pointed out in the claims hereto appended.

30 In the drawings, Figure 1 is an elevated front view of a pair of trousers constructed in accordance with the present invention. Fig. 35 2 is a fragmentary sectional view of the trousers, taken on line 2 2, Fig. 1.

Referring to the drawings by numerals, 1 designates the body portion of a pair of trousers to which is secured the cuff or belt securing and covering means 2. Cuffs 3 are also 40 formed upon the lowest portion of the legs of the trousers.

45 In the construction of the present invention I do not turn over a portion of the waist of the trousers, but add to the edge portion of the waist a cuff or belt securing means 2, which comprises in its construction a single piece of material which is folded at 4, thereby producing a folded strip 5, which is secured beneath 50 the outside portion of the cuff 2. The folded

portion 5 terminates near the upper portion 6 of the cuff 2, contiguous to the upper edge of the trousers 1. A stiffening-piece of material 7 is interposed between the outer and inner folded portion of the strip employed in the 55 construction of the cuff or belt securing and covering means 2 for the purpose of producing a comparatively stiff effect to the cuff.

An ordinary facing-piece 7^a is secured to the trousers, upon the inner sides thereof, at 8. 60 The fastening means employed in securing the facing-strip 7^a to the trousers is also used to secure the reinforced strip 2 to the trousers. The cuff or belt covering means 2 is also secured, preferably by stitching the same at 65 different parts thereof, to the body of the trousers, as is indicated at 9, thereby positively preventing the belt from becoming displaced when positioned upon the trousers beneath the cuff. The cuff 2 does not meet upon the front 70 of the trousers, but is separated so that the buckle 10 of the belt 11 will lie flush with the cuff 2 when the belt is positioned beneath the same. By this construction an artistic effect is produced, as it eliminates the undesirable 75 effect of exposing the entire belt to view when it is only desired that the buckle should be observed.

The stiffening means 7, positioned between the parallel portions of the cuff, produce a 80 reinforced covering for the belt, which is added to a pair of trousers of suitable length. By this construction it will be obvious that it is not necessary to turn over a portion of the upper edge of the trousers, thereby destroying 85 the construction of the trousers, as it will be obvious that if a cuff were formed from the integral part of an ordinary pair of trousers the size of the trousers would be destroyed.

The cuffs 3 3, secured to the legs of the trousers, are preferably formed integrally with the legs, although, if it is desired, they may be secured to the legs as cuff 2 is secured to the waist.

A pair of trousers constructed in accordance with the present invention is provided with cuffs formed upon the bottom of the legs and with a cuff upon the waist or body portion thereof, producing in appearance an artistic effect. 95 100

While I have described in the foregoing description and illustrated in the accompanying drawings the preferred construction of my invention, it will be apparent to one versed in the art to which this invention relates that certain alterations, modifications, and changes may be made, and I therefore reserve the right to make such alterations, modifications, and changes as shall fairly fall within the spirit and scope of the present invention.

Having thus fully described my invention, what I claim as new, and desire to secure by Letters Patent, is—

1. A pair of trousers having a cuff formed about the waist thereof and comprising a separate piece of material permanently secured to the trousers and having its outer edge folded under and against said piece, a reinforcing-strip interposed between the overlapping portions of the cuff, and equal in width to the folded portion of the cuff, the ends of the cuff being spaced apart, and means for fastening the outer edge of the cuff to the trousers.

2. In a device of the character described, the combination with a pair of trousers, of belt securing and covering means permanently positioned upon the waist thereof, comprising a single piece of material folded throughout its length, a reinforcing-strip interposed between the folded portion of said cuff, the ends of the

cuff terminating near each other producing an opened portion, a belt provided with a buckle and positioned upon said trousers, said buckle adapted to lie flush with the cuff within the opened portion formed between its ends. 35

3. In a device of the character described, the combination with a pair of trousers, of cuffs formed upon the bottom of its legs, a cuff formed near the upper edge of said trousers, comprising a separate piece of material permanently secured to the inner side of said trousers, and having its outer edge folded under and against said piece, the folded portion of said piece terminating near the upper edge of the trousers, a reinforcing-strip of the same 45 width of the folded portion of the piece of material interposed between the folded and outer portion of the cuff, the ends of said cuff terminating near each other, a belt provided with a buckle positioned beneath said cuff, 50 said buckle positioned between the ends of the cuff flush therewith, and fastening means connecting the outer edge of said cuff with the trousers.

In testimony whereof I affix my signature 55 in presence of two subscribing witnesses.

ROBERT ROCHMILL.
